United States Patent Office

Des. 213,921
Patented Apr. 22, 1969

213,921

COMPUTER OR THE LIKE

Kenneth A. Hopkins, Farmington, and George A. Connor,
Detroit, Mich., assignors to Burroughs Corporation, De-
troit, Mich., a corporation of Michigan

Continuation-in-part of design application Ser. No.
6,563, Apr. 3, 1967. This application Feb. 16, 1968,
Ser. No. 10,599

Term of patent 14 years

Int. Cl. D14—02

U.S. Cl. D64—11

Fig. 1.

Fig. 3.

Fig. 2.

Fig. 4.

FIG. 1 is a front perspective view of a computer or the like showing our new design;

FIG. 2 is a rear perspective view thereof;

FIG. 3 is a right side elevational view; and

FIG. 4 is a left side elevational view thereof.

This is a continuation-in-part of our design application Ser. No. D. 6,563, filed Apr. 3, 1967, and now abandoned.

We claim:

The ornamental design for a computer or the like, as shown and described.
